INTERFERENCE REDUCTION SYSTEM

Vernon D. Landon, Haddonfield, N. J., assignor
to Radio Corporation of America, a corporation
of Delaware

Application July 30, 1938, Serial No. 222,142

8 Claims. (Cl. 250—20)

This invention relates to interference reduction systems such as are utilized to eliminate undesired electrical impulses from the output of radio receiver apparatus or the like, and has for its principal object the provision of an improved system and method of operation whereby the output current of such apparatus is caused to assume a no-signal value when the level of the received impulses exceeds a predetermined value.

In my copending application Serial No. 222,141, filed July 30, 1938, assigned to the same assignee as the present application, there is disclosed a rejector limiter system in which the limiter cathode is swung positive with respect to the anode potential and the anode current is minimized or interrupted when the level of the received impulses increases to a predetermined value. The system of the aforesaid application has great utility as a radio frequency limiter, but is less satisfactory as an audio frequency limiter, for the reason that in the case of audio frequencies most effective elimination of the noise requires that anode current flow when the received impulse level is excessively high or during excessive positive swings of the input potential.

In its more specific aspects, the present invention provides an audio frequency limiter wherein the output current of the limiter is not interrupted but automatically assumes a zero signal value when the received impulse level increases to or exceeds a predetermined value. To this end, there is interposed between the audio frequency detector and the limiter an electron discharge device, the anode or plate current of which is interrupted in response to a predetermined received impulse level, the output of the audio frequency limiter during this interruption period being maintained at the level it normally assumes when no signal is received.

The invention will be better understood from the following description, considered in connection with the accompanying drawing, and its scope is indicated by the appended claims.

Referring to the drawing:

Figure 1 is a wiring diagram of the improved limiter system.

Figure 2 is the control grid potential-plate current characteristic of the limiter device, and

Figure 3 is the radio frequency input-limiter output characteristic of the improved system.

The system of Fig. 1 includes a tuned input circuit including a capacitor 10 and an inductor 11 through which the modulated carrier impulses are applied to the cathode and anode

electrodes of a detector 12. This input circuit also includes a radio frequency filter network 13—14—15 and a resistor 16. The detected modulation impulses produced in the resistor 16 are applied to the control grid 17 of an electron discharge device 18 through an input circuit which includes the grid 17, the resistor 16, the ground terminal 19, the lower section 20 of a bleeder resistor 21, and the cathode of the device 18.

The cathode-anode or output circuit of the device 18 includes a resistor 22 and a section 23 of the resistor 21. With these connections, the received impulses are amplified by the device 18 and applied to the control grid 24 of the limiter 25.

The limiter 25 is provided with an anode 26 to which is applied a relatively low potential, a screen grid 27 to which a relatively high potential is applied from the upper terminal of the resistor section 28, a cathode 29 which is connected to ground through a resistor 30, and a resistor 31 which is connected between the anode 26 and a grid 32 to afford a screening action, whereby greater output of the limiter is facilitated.

Fig. 2 illustrates the control grid potential-anode current characteristic of the limiter 25, grid potential being plotted as abscissae and anode currents as ordinates.

It will be observed that A and B are voltages of the control grid 24 which produce equal output current of the limiter 25. If the cathode-anode voltage of the device 18 (the potential of the resistor section 23) is so adjusted that B volts are applied to the control grid 24 when the cathode-anode current of the device 18 is cut off and, with zero signal at the detector 12, the voltage of the cathode of the device 18 is so adjusted that C volts are applied to the limiter control grid 24, the detector input-limiter output characteristic illustrated by Fig. 3 results. Otherwise stated, the limiter output assumes the normal no-signal value when the input becomes excessive. This condition during the overload or rejection period is highly advantageous in that the noise otherwise resulting from abrupt changes in output is avoided.

It should be understood (1) that this reduction in the output level of the limiter 25 in response to excessive input level is produced by the limiter cathode 29 being driven more positive due to the potential drop of the resistor 30, (2) that such excessive level also drives the grid 17 sufficiently negative to interrupt the output current 55

- of the device 18, and (3) that interruption of output current of the device results in the application to the limiter control grid 24 of a potential by which the limiter output is caused to assume the D value (Fig. 3), this potential being applied through an input circuit including the grid 24, the resistor 22, sections 23 and 20 of the resistor 21, the ground terminal 19, the resistor 30, and the cathode 29.
10. The voltage of the carrier applied to the detector 12 should be maintained by AVC or other suitable means at the value A in the center portion of the positive slope of the curve of Fig. 2. The modulating impulses then move up and down this portion of the curve and excessive input produces operation in the D region of the curve, resulting in a limiter output current equal to that for zero modulation.
- It is desirable, although not essential, that the 20 radio frequency channel ahead of the detector 12 be relatively broadly tuned. Following the limiter 25, of course, a normal audio amplifier may be provided.
- I claim as my invention:
25. 1. In an interference reduction system wherein modulated carrier impulses are applied to a channel including a detector coupled through an amplifier to the control grid of a limiter provided with a cathode, a cathode lead resistor, an anode and a screen grid, the method of operation which comprises reducing the output of said limiter to a level corresponding to normal zero modulation level during periods of excessive input, interrupting the output of said amplifier, and maintaining said limiter output at said level.
2. In an interference reduction system wherein modulated carrier impulses are applied to a channel including a detector coupled through an amplifier to the control grid of a limiter provided with a cathode, a cathode lead resistor, an anode and a screen grid, the method of operation which comprises applying a relatively low potential to said anode, applying a relatively high potential to said screen grid, interrupting the output of said amplifier during periods of excessive signal level, and applying to said control grid during said periods a potential to maintain the output of said limiter at its normal zero modulation 50 value.
3. The combination of a channel including a detector, an amplifier provided with input and output circuits and a limiter provided with input, control grid and screen grid circuits and having a normal zero modulation output current, means for applying a modulated carrier wave to said detector, means for interrupting the current of said amplifier output circuit when the output of said detector exceeds a predetermined 55 value, and means for maintaining the current of said limiter output circuit at its normal zero modulation value during said interruption.
4. The combination of a channel including a detector, an amplifier provided with input and output circuits and a limiter provided with input, output, control grid and screen grid cir-

cuits and having a normal zero modulation output current, means for applying a modulated carrier wave to said detector, means for interrupting the current of said amplifier output circuit when the output of said detector exceeds a predetermined value, and means including a potential source common to said amplifier output and said limiter control grid circuits for maintaining the current of said limiter output circuit at its normal zero modulation value during 10 said interruption.

5. The combination of a channel including a detector, an amplifier provided with input and output circuits and a limiter provided with input, output, control grid and screen grid circuits and having a normal zero modulation output current, means for applying a modulated carrier wave to said detector, means for interrupting the current of said amplifier output circuit when the output of said detector exceeds a predetermined value, and means including a resistor common to said amplifier output and said limiter control grid circuits for maintaining the current of said limiter output circuit at its normal zero modulation value during 20 said interruption.

6. The combination of a detector, means for applying a modulated carrier to said detector, a limiter including input, output and screen grid circuits and having a normal zero modulation output current, means for applying the output of said detector to said input circuit, and means for reducing the current of said output circuit to its normal zero modulation value when the modulation of said carrier exceeds a predetermined value.

7. The combination of a detector, means for applying a modulated carrier to said detector, a limiter including input, output and screen grid circuits and having a normal zero modulation output current, means for applying the output of said detector to said input circuit, means for applying a relatively low potential to said output circuit and a relatively high potential to said screen grid circuit, and means for maintaining the current of said output circuit at its normal 45 zero modulation value while the modulation of said carrier exceeds a predetermined value.

8. An interference reduction system comprising in combination a modulated carrier wave signal channel including a detector, an audio frequency amplifier tube having an input circuit coupled to said detector to receive the audio frequency signal output therefrom and having an output circuit, a limiter tube having a control grid coupled to the output circuit of said audio frequency amplifier and having an output anode and an output circuit connected therewith, means for applying a modulated carrier wave to said detector, means for interrupting the output of said amplifier when the output of said detector exceeds a predetermined value, and means for maintaining the anode current of said limiter tube at a value corresponding to substantially zero modulation during said interruption.
